UNITED STATES PATENT OFFICE.

GEORGE B. PORSCH, OF FORT WAYNE, INDIANA, ASSIGNOR TO VAN ARNAM MANUFACTURING COMPANY, A CORPORATION OF INDIANA.

VALVE-OPERATING DEVICE.

1,035,123.

Specification of Letters Patent.

Patented Aug. 6, 1912.

Application filed March 27, 1911. Serial No. 617,241.

To all whom it may concern:

Be it known that I, GEORGE B. PORSCH, a citizen of the United States of America, and resident of Fort Wayne, in the county 5 of Allen and State of Indiana, have invented certain new and useful Improvements in Valve-Operating Devices, of which the following is a specification.

This invention relates to improvements in 10 valve operating devices, of the class used in connection with flushing tanks, and the object of the improvement is to provide a simple device of its class in which the operation, for which it is intended, may be 15 effected by moving the handle either upward or downward. This object is accomplished by the construction illustrated by the accompanying drawings in which:

Figure 1 is a side elevation, in section, 20 showing the operating mechanism in connection with a flushing tank; Fig. 2 is a detail view showing the valve lever in a plane at right angles to that of Fig. 1; Fig. 3 is a plan view of the operating levers 25 in relative arrangement; and Fig. 4 is a detail showing a front elevation of the supporting bracket for the operating levers.

Similar numerals of reference indicate 30 corresponding parts throughout the several views, and referring now to the same:—1 is a flushing tank, and 2 is its lining.

3 is a valve that rests upon a seat 4 within the tank and closes the discharge outlet 5 of the tank. The outlet has in connection 35 therewith an over-flow pipe 6.

The construction of the outlet and over-flow pipe, the valve 3, its stem 7 and guide 8, the valve lever 9 and link 10, are of known construction and constitute the apparatus 40 which the present invention is intended to operate.

The invention comprises the two levers 11 and 12 respectively, suitably mounted, and connected with the apparatus to be operated. The lever 11 is of the third class

and has a fulcrum pin 13 at one end secured in the bracket 14. The rear end of the lever 11 has connection with one end of the valve lever 9 by means of a rod 15 that extends 50 up through an opening 16 in the tank 1. The hand lever 12 has a lateral stud 17 that extends through the lever 11 at a point thereon between its ends, and the hand lever, when pulled upward by its handle 18, acts 55 as a lever of the first-class, its fulcrum being the pin 13; and when pushed downward, acts as a lever of the second class, its fulcrum being the bearing 19 at the rear part of the bracket. The result of either 60 operation is that the rear end of the lever 11 is forced downward, thus actuating the valve lever, and in turn, the valve connected therewith.

Having described my invention what I 65 claim as new and desire to secure by Letters Patent is:—

1. In an operating device, a bracket having a pin at its forward end and a bearing point at its rear end; a lever of the third-class having said pin as a fulcrum at one of its ends, and a hand lever having pivotal connection with the lever of the third class between its ends and being adapted to operate when pulled upward as a lever of the 75 first-class, and when pushed downward as a lever of the second-class.

2. In a device of the class described, a bracket having two bearing parts arranged respectively at its ends, an actuating lever 80 having pivotal connection in the bracket, an operating lever having pivotal connection with the actuating lever and adapted to fulcrum against one of said bearing parts when moved downward and against the 85 other bearing part when moved upward.

GEORGE B. PORSCH.
